UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

CORK-PULLER.

SPECIFICATION forming part of Letters Patent No. 728,518, dated May 19, 1903.

Application filed August 16, 1902. Serial No. 119,847. (No model.)

To all whom it may concern:

Be it known that I, HENRY TSCHERNING, a citizen of the United States of America, residing at Freeport, in the county of Stephenson and State of Illinois, have invented certain new and useful Improvements in Cork-Pullers, of which the following is a specification.

My invention relates to certain new and useful improvements in cork-pullers; and its object is to provide a device of this class which shall be simple, cheap, and effective in operation.

The class of pullers to which my improved puller belongs is the type wherein a corkscrew-carrier and a threaded nut reciprocate in a suitable guideway, the nut and carrier moving together half-way up said guideway, the carrier leaving the nut and moving up along the remainder of the guideway to strip the cork, the carrier and nut then moving down, keeping the same distance apart until the nut reaches the bottom of the guideway, and the carrier then running down to the nut and screwing into the cork. This is one of several well-known types of pullers and, as heretofore explained, my improvements are in pullers of this type.

My invention consists more particularly in the devices which are used to cause the corkscrew-carrier and the nut to preserve the proper relative positions—that is to say, the devices which lock them together during the first half of their upward movement, permit them to separate during the second half of the upward movement, keep them at a constant distance apart during the first half of the downward movement of the carrier, and permit them to come together during the last half of the downward movement of the carrier. Hitherto the practice has been to use a system of positive locks between the corkscrew-carrier and the threaded nut, two hooks or some similar device being usually used. In my puller I dispense with both of these hooks, replacing the positive lock between the carrier and the nut by a different device, which will be explained in due course.

The invention herein illustrated is a further development of the broad idea illustrated in an application filed on even date herewith on

cork-pullers, and allotted Serial No. 119,849. The broad idea contained in both these applications is the controlling of the relative movement of the corkscrew-carrier and nut by preventing the rotation of the corkscrew rather than by positively moving them, as has been done heretofore.

My invention is fully illustrated in the drawings accompanying this specification and fully described in this specification.

In the aforesaid drawings, Figure 1 is an elevation of the parts of my improved puller, one of the side plates of the case being removed. Fig. 2 is a similar view showing the nut and corkscrew-carrier in central longitudinal section. Fig. 3 is a section in the line 3-3 of Fig. 2. Fig. 4 is a vertical section in line 4-4 of Fig. 2. Fig. 5 is an enlarged vertical longitudinal section through the corkscrew-carrier, the line of section being indicated by 5-5 in Fig. 6. Fig. 6 is a horizontal section in the line 6-6 of Fig. 1, and Fig. 7 is a front view of the cork-extractor with the handle partly broken away.

In the drawings, A is the case of the cork-puller, made in the usual form from two pieces A' A''. These two pieces are so formed as to leave two openings a a' on their front side, these openings being separated by a stop a''. A longitudinal guideway a''' extends throughout the greater portion of the length of the case. In this guideway runs a nut B, threaded in the usual way to permit the corkscrew to run through it and provided with a lug b, extending into the opening a', and adapted to engage the stop a'' at the upper end of this opening. It is obvious, of course, that the nut is free to move under proper impulse up and down through the guideway, its motion downward being limited by the guideway a''' and movement in the opposite direction being limited by engagement of the lug b with the portion a''. A corkscrew-carrier C runs in the guideway a''' above the nut B, and in this corkscrew-carrier is secured a corkscrew D of the ordinary type, which runs, as heretofore mentioned, through a suitably-threaded portion in the nut B. The corkscrew D is of course rotatable in the corkscrew-carrier C in the usual way. A lever E is

is pivoted in the case, and this lever is connected, by a suitable link *e*, to the corkscrew-carrier *C*. It is obvious, of course, that the movement of the handle *E* will reciprocate the carrier *C*. The means by which the relative movements of the carrier and the nut are controlled consists, as heretofore pointed out, in preventing rotation of the corkscrew itself in its seat in the carrier during certain portions of the movement of the carrier. The means by which the power to rotate on the part of the corkscrew is controlled is by two ratchets *G* *G'* upon the top of the corkscrew. The teeth on each of these ratchets extend in opposite directions, so that by engagement with a suitable pawl each can prevent the rotation of the corkscrew in one direction. The ratchet *G'* prevents rotation to the right and the ratchet *G* prevents rotation to the left when engaged by the proper pawl. Upon the carrier are pivoted two pawls *H* *H'*, adapted to engage the ratchets *G* *G'*, respectively. These pawls are pressed by springs *h* *h'* toward the ratchets *G* *G'*.

It is obvious that with the ordinary right-handed screw the corkscrew must be permitted to turn to the right when entering the cork—that is, when in the position shown in Fig. 2—and must be permitted to turn to the left when stripping—that is, when the corkscrew-carrier is being separated from the nut in the upper portion of the movement of said carrier. Similarly, when it is desired to have the nut and carrier move together—that is, when pulling the cork—the corkscrew must be prevented from left-handed rotation—that is, it must be prevented from unscrewing and pulling out through the nut. Likewise when it is desired to have the nut and carrier move downward from the position shown in Fig. 1 it is necessary that the corkscrew be prevented from right-hand rotation—that is, that it be prevented from screwing into and through the nut. To accomplish these results, the pawl *H'* must be engaged with the ratchet *G'* when moving down from the position shown in Fig. 7, thereby preventing right-hand rotation. It is immaterial whether or not left-hand rotation is possible. When the nut reaches the bottom of its course, the pawl *H'* must be released from its engagement with the ratchet *G'* in order that the corkscrew may enter the cork. It is immaterial, of course, whether or not the corkscrew is free to rotate to the left during this portion of its motion, for the reason that there is no tendency for it to so rotate. When the pulling motion begins, however, the pawl *H* must be in engagement with the ratchet *G* in order to prevent left-handed rotation. It is of course wholly immaterial whether or not the corkscrew can rotate to the right when pulling, as there is no tendency for it to so rotate. When the stripping motion is begun and the nut is arrested, the pawl *H* must be released in order to permit left-hand rotation. It is, however, immaterial whether

there is any right-hand rotation. This brings us back to the beginning of the cycle. The motion of the pawls is controlled by two ribs *I* *I'*, cast in and extending from the opposite halves of the case *A*. The rib *I'* is in the bottom of the case, and its position is such that in the lower half of the motion of the corkscrew-carrier the pawl *H'* is held out of engagement with the ratchet *G'*. This leaves the corkscrew free to rotate to the right. The rib *I* does not reach the bottom of the case, and the spring *h* therefore holds the pawl *H* in engagement with the ratchet *G* and prevents left-hand rotation of the corkscrew when the corkscrew-carrier is in the lower half of the case. This, it will be seen, gives exactly the motion which it ought to have—that is, it will enter the cork, turning to the right, but cannot unscrew by turning to the left when pulled backward. In the upper half of the case the state of affairs is reversed. We find the rib *I* holding the pawl *H* away from the ratchet *G*, permitting left-hand rotation, while the spring *h'* holds the pawl *H'* in contact with the ratchet *G'*, preventing right-hand rotation. This, it will be seen, permits the cork to be stripped, but prevents the carrier from approaching the nut when the two ought to move down and keep the same distance apart.

The simplicity and effectiveness of this device will be readily apparent to any one having any knowledge of the complicated systems heretofore in use for securing the proper motion of the corkscrew and carrier. This form is extremely simple and cheap and exceedingly effective.

I realize that considerable changes can be made in the details of construction, and I do not, therefore, desire to limit my invention to the exact construction shown.

I claim as new and desire to secure by Letters Patent—

1. In a device of the class described, the combination with a frame, a corkscrew-carrier and means for reciprocating the same, a corkscrew rotatably secured in said carrier and a nut non-rotatably guided in said frame and threaded to embrace said corkscrew, of means independent of said nut for preventing retrograde revolution on the part of said corkscrew during the first portion of the rise of said carrier, substantially as described.

2. In a device of the class described, the combination with a frame, a corkscrew-carrier and means for reciprocating the same, a corkscrew rotatably secured in said carrier and a nut non-rotatably guided in said frame and threaded to embrace said corkscrew, of means on said corkscrew-carrier for preventing retrograde revolution on the part of said corkscrew during the first portion of the rise of said carrier, substantially as described.

3. In a device of the class described, the combination with a frame, a corkscrew-carrier and means for reciprocating the same, a corkscrew rotatably secured in said carrier

and a nut non-rotatably guided in said frame and threaded to embrace said corkscrew, of a ratchet on said corkscrew and a suitable pawl adapted to prevent retrograde rotation on the 5 part of said corkscrew during the first portion of the rise of said carrier, substantially as described.

4. In a device of the class described, the combination with a frame, a corkscrew-carrier and means for reciprocating the same, a corkscrew rotatably secured in said carrier and a nut non-rotatably guided in said frame and threaded to embrace said corkscrew, of a ratchet on said corkscrew and a pawl on said 15 corkscrew-carrier adapted to prevent the retrograde revolution on the part of said corkscrew during the first portion of the rise of said carrier, substantially as described.

5. In a device of the class described, the combination with a frame, a corkscrew-carrier and means for reciprocating the same, a corkscrew rotatably secured in said carrier and a nut non-rotatably guided in said frame and threaded to embrace said corkscrew, of a 20 ratchet on said corkscrew, a pawl on said carrier adapted to prevent the retrograde revolution of said corkscrew during the first portion of the rise of said carrier, and means for throwing said pawl out of engagement with 25 said ratchet during the second portion of the rise of said corkscrew-carrier, substantially as described.

6. In a device of the class described, the combination with a frame, a corkscrew-carrier and means for reciprocating the same, a corkscrew rotatably secured in said carrier and a nut non-rotatably guided in said frame and threaded to embrace said corkscrew, of a ratchet on said corkscrew, a pawl on said 30 carrier adapted to prevent the retrograde revolution of said corkscrew, during the first portion of the rise of said carrier, and a rib on said case adapted to hold said pawl out of engagement with said ratchet during the second 35 portion of the rise of said carrier, substantially as described.

7. In a device of the class described, the combination with a frame, a corkscrew-carrier and means for reciprocating the same, a corkscrew rotatably secured in said carrier and a nut non-rotatably guided in said frame and threaded to embrace said corkscrew, of a ratchet on said corkscrew and a suitable 40 pawl adapted to prevent forward rotation on the part of said corkscrew during the first portion of the downward motion of said carrier, substantially as described.

8. In a device of the class described, the combination with a frame, a corkscrew-carrier and means for reciprocating the same, a corkscrew rotatably secured in said carrier and a nut non-rotatably guided in said frame and threaded to embrace said corkscrew, of a ratchet on said corkscrew and a pawl on 45

said corkscrew-carrier adapted to prevent the 65 forward revolution on the part of said corkscrew during the first portion of the downward motion of said carrier, substantially as described.

9. In a device of the class described, the 70 combination with a frame, a corkscrew-carrier and means for reciprocating the same, a corkscrew rotatably secured in said carrier and a nut non-rotatably guided in said frame and threaded to embrace said corkscrew, of 75 a ratchet on said corkscrew, a pawl on said carrier adapted to prevent the forward revolution of said corkscrew, during the first portion of the downward motion of said carrier, and means for throwing said pawl out of engagement with said ratchet during the second 80 portion of the downward motion of said corkscrew-carrier, substantially as described.

10. In a device of the class described, the combination with a frame, a corkscrew-carrier and means for reciprocating the same, a corkscrew rotatably secured in said carrier and a nut non-rotatably guided in said frame and threaded to embrace said corkscrew, of 85 a ratchet on said corkscrew, a pawl on said 90 carrier adapted to prevent the forward revolution of said corkscrew, during the first portion of the downward motion of said carrier, and a rib on said case adapted to hold said pawl out of engagement with said ratchet 95 during the second portion of the downward motion of said carrier, substantially as described.

11. In a device of the class described, the combination with a frame, a corkscrew-carrier and means for reciprocating the same, a corkscrew rotatably secured in said carrier and a nut non-rotatably guided in said frame and threaded to embrace said corkscrew, of 100 two ratchets on said corkscrew, the teeth of 105 said ratchets extending in the opposite direction, a pawl on said carrier adapted to prevent the retrograde revolution of said corkscrew during the first portion of the rise of said carrier, a rib on said case adapted to hold 110 said pawl out of engagement with its ratchet during the second portion of the rise of said carrier, a second pawl on said carrier adapted to prevent the forward rotation of said corkscrew during the first portion of the 115 downward motion of said carrier and a second rib on said case adapted to hold said second pawl out of engagement with its ratchet during the second portion of the downward motion of 120 said carrier, substantially as described.

In witness whereof I have hereunto set my hand, at Freeport, in the county of Stephenson and State of Illinois, this 26th day of July,

A. D. 1902.

HENRY TSCHERNING.
